US00D476668S

(12) **United States Design Patent** (10) Patent No.: **US D476,668 S**
 Storer et al. (45) Date of Patent: ** Jul. 1, 2003

(54) **ABRASIVE MEDIA DELIVERY DEVICE**

(75) Inventors: **Ron D. Storer**, Fullerton, CA (US);
Robert A. Robinson, Glenwood, NM (US); **Lance G. Nord**, Huntington Beach, CA (US); **Stephen C. McGrady**, Hesperia, CA (US)

(73) Assignee: **Media Blast & Abrasives, Inc.**, Brea, CA (US)

(**) Term: **14 Years**

(21) Appl. No.: **29/164,687**

(22) Filed: **Jul. 29, 2002**

(51) LOC (7) Cl. **15-09**

(52) U.S. Cl. **D15/124**

(58) Field of Search D15/124; 451/75, 451/88-90, 99, 100, 101, 410, 426, 438
